UNITED STATES PATENT OFFICE.

LEWIS S. MOORE, OF MINNEAPOLIS, MINNESOTA.

MATCH BOX.

Application filed February 12, 1923. Serial No. 618,676.

To all whom it may concern:

Be it known that I, LEWIS S. MOORE, a citizen of the United States, residing at Minneapolis, in the county of Hennepin and State of Minnesota, have invented certain new and useful Improvements in Match Boxes; and I do hereby declare the following to be a full, clear, and exact description of the invention, such as will enable others skilled in the art to which it appertains to make and use the same.

My invention relates to match boxes of the type disclosed and broadly claimed in my co-pending application filed Nov. 10, 1921, under Serial Number 514,233, and has for its object to improve the same in the several particulars hereinafter noted.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a front elevation of the improved match box;

Fig. 2 is a view in vertical section taken on the line 2—2 of Fig. 1;

Fig. 3 is a fragmentary view corresponding to Fig. 2 with the exception that certain parts have been moved into different positions;

Fig. 4 is a perspective view of the back plate and parts carried thereby;

Fig. 5 is a perspective view of the box filled with matches;

Fig. 6 is a fragmentary perspective view showing the lower end portion of the box;

Fig. 7 is a view principally in horizontal section taken on the line 7—7 of Fig. 1, on an enlarged scale; and

Fig. 8 is a perspective view of the feed blade.

The numeral 9 indicates a sheet metal back plate, the lower end portion of which is folded outward upon itself and laterally spaced to afford a pocket 10 having open sides. Box capping flanges 11 are afforded by turning the vertical and top edge portions of the back plate 9 outward at right angles. The ends of the top capping flange 11 terminate short of the side capping flanges 11 to afford notches 12, for a purpose that will presently appear. The lower

end portions of the side capping flanges 11 extend across the upper end portions of the open sides of the pocket 10 and are folded onto the outer face thereof and soldered or otherwise rigidly secured thereto to firmly hold the upper upturned portion of the back plate 9 and reinforce the outer upper end portions of the pocket 10 to afford hinge lugs 13.

An open back sheet metal box or receptacle 14 for matches is removably applied to the back plate 9 within the capping flanges 11 and normally closed thereby. The hopper bottom 15 of the box 14 terminates short of the back plate 9 to afford a narrow match escape passageway 16, and said hopper bottom is so arranged as to direct the matches toward the back plate 9 and over the match escape passageway 16. The sides of the box 14 are extended below the hopper bottom 15 and have formed therein V-shaped hinge notches 17 arranged to receive the hinge lugs 13 and hingedly and removably support the box 14 for swinging movement to and from a position in which the open back thereof is closed by the back plate 9.

The top 18 of the box 14 is upwardly inclined, and free from the sides of said box to permit said top to be sprung under the top capping flange 11 during the closing of the box 14 and lock the same closed with a yielding pressure. During this closing of the box 14 the sides thereof enter the notches 12. It will be noted that the inner edges of the hinge notches 17 are beveled to form cams 19 for engagement with the inner faces of the hinge lugs 13 and move said box rearward against the back plate 9 during the closing thereof.

The sides of the box 14, forward of the hinge notches 17, are bent laterally toward each other, as best shown in Fig. 5, to afford match holders 20 at the top of the pocket 10. It will be noted that these match holders 20 are endwise spaced and made transversely convex to receive and hold a match, removed from the box 14 as will presently appear, in a position in which it may be easily grasped at its intermediate portion between the thumb and forefinger. The inner edge portions of the holders 20 are substantially flush with the top of the pocket 10 and are closely positioned in respect thereto.

The match escape passageway 16 is normally closed by an escapement 21 loosely

pivoted on a fixed rod 22 which extends through bores in the depending sides of the box 14 substantially above the hinge notches 17. The outer projecting ends of the escapement 21 are bent laterally at 23 into depressed seats 24 and hold the rod against endwise movement, and which seats hold said rod from turning. A leaf spring 25 secured to the hopper bottom 15 bears against 10 the escapement 21 and yieldingly holds the same in a position to normally close the match escapement passageway 16 as shown in Fig. 2. To move the escapement 21 into a position to open the passageway 16 and 15 remove a single match at a time from the box 14, there is mounted in the pocket 10 a feed blade 26, the upper end portion of which is folded upon itself and then laterally rearward to form a match-supporting ledge 27. The feed blade 26 is operated by a bail 28 pivoted to the side capping flanges 11 and connected by arms 29 to said feed blade by a rod 30 mounted in a pair of ears 31 on the lower corners of said feed blade and 25 working in the open sides of the pocket 10.

To remove a match from the box 14 the bail 28 is first raised to project the feed blade 26 and thereby, with a striking action on the escapement 21, lock the same into 30 an inoperative position against the tension of the spring 25 and then enter the box 14 through the passageway 16 and pick up one of the matches on its shoulder 27, as shown in Fig. 3. A return movement of the 35 bail 28 will retract the feed blade 26, and as the same moves past the escapement 21, said escapement is again returned to normal position by the spring 25 to close the passageway 16. A pair of cam fingers 32 40 pressed from the back plate 9, between the pocket 10 and escapement 21, intercept the match on the shoulder 27, and as the feed blade 26 moves below said fingers, the match held thereon is directed onto the holders 45 20. Notches 33 are formed in the shoulder 27 to afford clearance for the cam fingers 32.

The face of the pocket 10 is roughened, by pressing the same, to afford a striking surface 34 on which the matches may be 50 lighted. Apertures 35 in the back plate 9 are arranged to interlock the nails 36 driven into a wall or other support 37 to support the match box. As is well known, matches are held in the boxes in which they are 55 packed by a cardboard strip, the ends of which are bent laterally and extended into the box at the ends thereof. In filling the match box 14, the matches are poured therein from their original container and the 60 cardboard strip used in holding the same in place is used in holding the matches in the box 14, as shown in Fig. 5, while the same is being attached to the back plate 9. This cardboard strip is indicated by the 65 character *y*, and the lower end thereof in-

serted between the matches and the bottom of the box 14, and the other end thereof is left projected above said box so that the same may be withdrawn just before the top 18 is sprung under the top capping 70 flange 11.

What I claim is:

1. In a match box the combination with a back plate having top and side capping flanges, of a box having an open back, a separable hinge supporting the box for swinging movement to and from a position in which it is closed by the back plate and held by the capping flanges, the top of the box being adapted to be sprung under the top of the capping flange to hold the box closed and the members of the separable hinge interlocked, and a feed blade for removing matches from the box. 75 80 85

2. In a match box the combination with a back plate having top and side capping flanges and a pocket in its lower portion, of a box having an open back, said box having notches in its sides to receive the upper edge of the front of the pocket to hingedly connect said box thereto for swinging movement to and from a position in which it is closed by the back plate and held by the capping flanges, the top of the box being adapted to be sprung under the top capping flange 90 95 to hold the box closed, and a feed blade mounted in the pocket for removing matches from the box. 100

3. In a match box the combination with a back plate having top and side capping flanges, the bottom portion of said back plate being folded outward upon itself to afford a pocket, of a box having an open back, said box having notches in its sides to receive the upper edge of the front of the pocket to hingedly connect said box thereto for swinging movement to and from a position in which it is closed by the back plate and held by the capping flanges, the top of the box being adapted to be sprung under the top capping flange to hold the box closed, and a feed blade mounted in the pocket for removing matches from the box. 105 110 115

4. The structure defined in claim 3 in which the upturned portion of the back plate is attached to the side capping flanges. 120

5. The structure defined in claim 3 in which the notches have cam surfaces arranged to move the box toward the back plate during the closing thereof. 125

6. The structure defined in claim 3 in which the side capping flanges afford stops to limit the lifting movement of the feed blade. 130

7. In a match box the combination with a back plate, a box having an open back, means for holding the box in a position in which it is closed by the back plate, the sides of the box being turned toward each 135

other to afford match holders, the lower portion of the front of the box being turned inward to afford an inclined bottom spaced above said match holders, and a feed blade 5 for removing matches from the box and delivering the same to said holders.

8. In a match box the combination with a back plate, a box having an open back, means for holding the box in a position 10 in which it is closed by the back plate, the sides of the back plate being extended below the bottom of the box and turned toward each other to afford match holders, said box having in its bottom a match es-

cape passageway, a hinge rod extending 15 through the depending sides of the box and bent laterally into depressed seats in the outer face of said sides, an escapement loosely pivoted on the hinge rod, a spring operative on the escapement and under strain 20 to hold the same in a position to close said passageway, and a feed blade arranged to operate the escapement to open said passageway and remove a match from the box.

In testimony whereof I affix my signature. 25

LEWIS S. MOORE.
